UNITED STATES PATENT OFFICE.

WILLIAM CORRY, OF CINCINNATI, OHIO, ASSIGNOR TO THE HALL'S SAFE COMPANY, OF SAME PLACE.

CIRCULAR DOOR FOR SAFES.

SPECIFICATION forming part of Letters Patent No. 590,943, dated September 28, 1897.

Application filed June 1, 1897. Serial No. 638,876. (No model.)

To all whom it may concern:

Be it known that I, WILLIAM CORRY, a citizen of the United States, and a resident of Cincinnati, in the county of Hamilton and State of Ohio, have invented certain new and useful Improvements in Circular Doors for Burglar-Proof Safes, of which the following is a specification.

My invention relates to that class of burglar-proof safes provided with a circular door which is opened and closed by screw-threaded connection between the inner face of the door and its jamb and held in the closed position under guard of a time-lock.

The object of the invention is to provide means to securely hold the different plates of a door together without perforating the outer plate.

The invention will be first fully described in connection with the accompanying drawings and then particularly referred to and pointed out in the claims.

In the drawings, Figure 1 is a transverse sectional view of the front of a safe embodying my invention. The door is shown in horizontal diametrical section on the right and partly in elevation and partly in radial diagonal section on the left of the vertical center, the section being taken through lines $x-x$ of Fig. 2. Fig. 2 is a front elevation.

The door in both views is shown in the closed position.

The safe-body A, the support B, secured to the outside of the door, its handle b, and the crane-hinge C, in which the support is pivoted, are of ordinary construction and so well known that they need not be specifically described.

The outer plate of the door D is centrally recessed, the recess extending about half-way through the plate, leaving an annular flange d extending around its inner edge. The inner wall of this flange is tapped to receive the circular exteriorly-screw-threaded disk or plate E, which is about the same thickness as the plate D. One half of the plate E is embedded in the plate D, and the other half projects to enter the interiorly-rabbeted ring F, which is screwed onto the disk or plate E. The inner opening in the ring F is tapped to receive the exteriorly-screw-threaded disk G,

which is screwed down against the plate or disk E. The rabbeted and screw-threaded ring H is screwed tightly against the inner face of the ring F. The ring H is screw-threaded exteriorly to engage the screw-threads a in the inner reduced opening of the jamb, whereby the door is closed by turning it in one direction and opened to disengage the ring H from the jamb when turned in the opposite direction in the usual way.

The parts D, E, F, and G may be either of roll-tempered or laminated steel and of any number and thickness desired. The engaging collar H is preferably of cast steel.

In constructing my improved door, the parts being formed as shown in Fig. 1 and the plate D tapped and screw-threaded in proper place to receive the bolt f, the ring F also perforated and countersunk on the inner face to receive the shank and head of said bolt, and the disk G being also bored and tapped to receive the screw-bolts g, and the inwardly-projecting flange of the ring or collar H being perforated and countersunk to pass the shank and embed the heads of said screws g, the disk or plate E is first screwed tightly into the plate D and the ring F then turned around until its inwardly-projecting flange and its abutting face fit tightly against the inner faces of the plate D and ring E. The bolts f are then inserted to prevent unscrewing the ring. The disk G is then tightly screwed in place in the ring F and against the face of the plate or disk E, the collar H screwed tightly down over the said disk G, and the screws g tightened into place, completing the door. It will thus be seen that even if the crane-hinge and support B were broken away there would be no exposed bolt-head that could be acted upon or broken away either by the ordinary burglar-tools or an opening made near its joint in which to insert dynamite for the purpose of loosening or breaking the bolts and separating the plates. I have shown the interior bolts for holding the plates from revolving, but it is evident that keys or other means may be employed instead.

What I claim is—

1. In a round door for safes the combination of the outer plate interiorly recessed and screw-threaded, the inner rabbeted and in-

teriorly-screw-threaded rings and the circular plates or disks to lock the said rings and outer plate together, substantially as shown and described.

5 2. The combination of the interiorly-recessed outer plate, the inner rabbeted peripheral rings, the circular disks locked to said outer plate and rings by screw-threaded con-

nexion, and the bolts to prevent the parts from turning, substantially as hereinbefore set forth.

WILLIAM CORRY.
